DESIGN FOR A NECKLACE

Alfred Philippe, New York, N. Y., assignor to Trifari, Krussman & Fischel, Inc., New York,
N. Y.

Application January 28, 1938, Serial No. 74,663

Term of patent 3½ years

To all whom it may concern:

Be it known that I, Alfred Philippe, a citizen of the United States, residing at New York, in the county and State of New York, have invented a new, original, and ornamental Design for a Necklace, of which the following is a specification, reference being had to the accompanying drawing, forming part thereof, wherein—

Fig. 2 is a side elevation of one-fifth of a necklace showing my new design, the other four-fifths being a duplicate and continuation of that shown.

I claim:

The ornamental design for a necklace substantially as shown and described.

ALFRED PHILIPPE.
